Primary Examiner — Eliza Z Bennett-Hattan(74) *Attorney, Agent, or Firm* — McKee, Voorhees & Sease, PLC(57) **CLAIM**

I claim the ornamental design for a pocket tape rule holder assembly, as shown and described.

DESCRIPTION

FIG. 1 is a perspective view of the pocket holder assembly for a tape measure, according to the present invention.

FIG. 2 is a front elevation view of the assembly.

FIG. 3 is a rear elevation view of the assembly.

FIG. 4 is an elevation view from one side of the assembly, with the opposite side being a mirror-image.

FIG. 5 is a top plan view of the assembly; and, FIG. 6 is a bottom plan view of the assembly.

The broken lines in the drawings are included for the purpose of illustrating subject matter that forms no part of the claimed designed. No claim is made to a specific size or scale. The tool engaging member of the pocket rule holder assembly is shown with a symbolic break in its length. The appearance of any portion of the tool engaging member between the break lines forms no part of the claimed design.
